APPARATUS FOR HOLDING A DOOR OPEN

Frank L. Mann, Le Mesa, Calif.

Application February 3, 1936, Serial No. 62,157

5 Claims. (Cl. 292—263)

My invention relates to an apparatus for holding a door open, more particularly used for garage doors or the like, and the objects of my invention are:

- 5 First, to provide an apparatus for holding a door open which will hold the door against ordinary wind pressure but may be closed by simply taking hold of the door and forcing it in closed position.
- 10 Second, to provide an apparatus of this class which is automatic in its action so that when the door is open to a position substantially at right angles to the door opening it is latched against closing but may be closed by pressure on the free 15 side of the door only.

Third, to provide an apparatus of this class which is wholly automatic in its action and only requires manual pressure for operation.

Fourth, to provide an apparatus of this class 20 which is supported at the top of the door and in the door casing above the door so that it is up out of the way.

Fifth, to provide an apparatus of this class 25 which is very simple and economical of construction, easy to operate, easy to install, efficient in its action and which will not readily deteriorate or get out of order.

With these and other objects in view as will appear hereinafter, my invention consists of certain novel features of construction, combination, 30 and arrangement of parts and portions as will be hereinafter described in detail and particularly set forth in the appended claims, reference being had to the accompanying drawing and to the 35 characters of reference thereon which form a part of this application in which:

Figure 1 is a top or plan view of my apparatus shown in relation with the door which is fully open; Fig. 2 is a similar view showing the position 40 of the apparatus with the door partially closed and showing by dotted lines its full open position; Fig. 3 is a side elevational view from the line 3—3 of Fig. 1; Fig. 4 is an enlarged fragmentary top view showing the main operating portions of the 45 structure in their position shown in Fig. 1 of the drawing; Fig. 5 is a similar view showing the same in their position after starting to close the door; Fig. 6 is a similar view showing the position 50 of the operating parts when the door is about one-half closed; Fig. 7 is a sectional view from the line 7—7 of Fig. 4; and Fig. 8 a sectional view from the line 8—8 of Fig. 4.

Similar characters of reference refer to similar parts and portions throughout the several views 55 of the drawing.

The bar 1, roller 2, roller supporting pin 3, latch member 4, latch screws 5, bar 6, spring 7, and latch member 8, constitute the principal parts and portions of my apparatus for holding a door open.

The bar 1, is pivotally mounted on a bifurcated bracket 1a, which is secured outwardly on the door toward the free side near the upper end thereof as shown best in Figs. 1 and 3 of the drawing, the door being designated D. This bar 10 1 is provided with a pin 3 secured therein extending from the normally upper side thereof as shown best in Fig. 4 of the drawing. Revolubly mounted upon this pin 3 is a roller 2 and said roller spaced from the upper side of the bar 1 15 at its lower side substantially the thickness of the bar 6 which is inserted between the roller 2 and the bar 1. Secured on the opposite end of the bar 1 from the bracket 1a is a latch member 4 which is U-shaped as shown best in Fig. 7 of the drawing and is adapted to receive the member 6 which is shiftably mounted therein. This U-member 4 is provided in its normally upper side with a slot 4a which is adapted to receive the body of the screw 5 which is adapted to be shifted into and out of said slot 4a with the longitudinal shifting of the bars 1 and 6 relatively to each other. The extended end of the bar 6 is provided with a hole 6a therein shown best in Fig. 3 of the drawing, adapted to receive a screw 20 or pin for pivotally supporting the bar 6 in the door frame at the upper side thereof. The bar 6 is provided with a screw 6b for securing the one end of the spring 7 which is a tension spring. The opposite end of the spring 7 connects with the latch member 8 at its free end at point 8a. This latch member 8 is pivotally mounted at 8b near the end of the bar 6. This latch 8 has a circular notch 8c which is adapted to receive the roller 2 as shown in Fig. 4 of the drawing when the apparatus is in extended position and the door open. Thus the member 8, together with the roller 2, provides a latch to prevent longitudinal compression of the apparatus for all ordinary purposes and to resist ordinary wind pressure against the door. However, by a greater manual pressure against the door the spring 7 is extended, the latch 8 moves outwardly as shown in Fig. 5 of the drawing and permits the longitudinal compression of the apparatus and the 25 notch 4a together with the screw 5 prevent angular shifting of the bars 1 and 6 relatively to each other so long as the latch 8 is in latched position as shown in Fig. 4 of the drawing, but permits angular shifting with the longitudinal shifting 30 35 40 45 50 55 60 65 70 75 80 85 90 95 100 105 110 115 120 125 130 135 140 145 150 155 160 165 170 175 180 185 190 195 200 205 210 215 220 of the members 1 and 6. The bar 6 is also provided with an annular slot 6c in which the pin 3 is slidably mounted and roller 2 overhangs the edges thereof. This slot 6c is provided at its one end with an enlarged portion 6d in slight offset relation with the slot 6c to form a slight catch in connection with the pin 3 when the members 1 and 6 have been shifted towards each other a sufficient distance with the closing of the door 10 D, as will be seen in Fig. 6 of the drawing.

The operation of my apparatus is as follows: Taking Fig. 1 to start with, the door in Fig. 1 is shown supported at substantially 90 degrees from its closed position. By exerting sufficient pressure on the door in an attempt to close the same, the latch 8 is forced outwardly by the roller 2 against the tension of the spring 7. The pin 3 supporting said roller 2 shifts in the cam slot 6c towards the offset portion 6d at the same time the screw 5 moves outwardly in the slot 4a in the member 4 as shown best in Fig. 5 of the drawing, and when the pin 3 reaches the offset portion 6c the screw 5 is entirely out of the slot 4a and further movement of the door will cause the bars 1 and 6 to turn to positions at right angles to each other as shown in Fig. 6 of the drawing and the continuing of the closing of the door will cause the bar members 1 and 6 to come toward a parallel relation to each other until the door 30 is closed and this action is reversed in opening the door. When the door is open the spring tension on the latch 8 causes the notch 8c in the latch to engage the roller 2 thus holding the door against considerable pressure which may be overcome by a greater manual pressure and overcoming the spring tension of the spring 7.

Although I have shown and described a particular construction, combination, and arrangement of parts and portions, I do not wish to be limited to this particular construction, combination, and arrangement, but desire to include in the scope of my invention the construction, combination, and arrangement substantially as set forth in the appended claims.

Having thus described my invention, what I claim as new and desire to secure by Letters Patent is:

1. In an apparatus for holding doors open, a bar with one end pivotally connected to a door, another bar with one end pivotally connected to the door frame above the door, the free end of said bars pivotally connected in overlapped relation to each other, a pair of latch members on each of said bars in engageable relation with a pair of latch members on the other bar, and said latch members including a spring controlled latch on one of said bars engageable by a cam controlled roller on the other of said bars to prevent longitudinal shifting of said bars under ordinary pressure.

2. In an apparatus for holding doors open, a bar with one end pivotally connected to a door, another bar with one end pivotally connected to the door frame above the door, the free end of said bars pivotally connected in overlapped relation to each other, a pair of latch members on each of said bars in engageable relation with a pair of latch members on the other bar, said latch members including a spring controlled latch on one of said bars engageable by a cam controlled roller on the other of said bars, to prevent longitudinal shifting of said bars under ordinary pressure, and also including a slotted latch and guide on one of said bars and a screw on the other of said bars longitudinally shiftable in the slot.

3. In an apparatus for holding a door open, a bar pivotally connected at one end to the inner side of a door, another bar pivotally connected to the door frame above the door, said bars pivotally connected together near their opposite ends but shiftable slightly longitudinally, and engageable lapped members on each of said bars arranged to prevent longitudinal relative shifting of said bars under ordinary pressure.

4. In an apparatus for holding a door open, a bar pivotally connected at one end to the inner side of a door, another bar pivotally connected to the door frame above the door, said bars pivotally connected together near their opposite ends but shiftable slightly longitudinally, engageable lapped members on each of said bars arranged to prevent longitudinal relative shifting of said bars under ordinary pressure, latch means on each of said bars arranged to prevent angular relative shifting of said bars until they have been longitudinally shifted, and spring tension means in connection with said longitudinally shiftable latch means.

5. In an apparatus for holding a door open, a bar pivotally connected at one end to the inner side of a door, another bar pivotally connected to the door frame above the door, said bars pivotally connected together near their opposite ends but shiftable slightly longitudinally, engageable lapped members on each of said bars arranged to prevent longitudinal relative shifting of said bars under ordinary pressure, latch means on each of said bars arranged to prevent angular relative shifting of said bars until they have been longitudinally shifted and spring tension means in connection with said longitudinally shiftable latch means, and angular slot means in one of said bars in operative relation with one of said latch members to prevent angular shifting of said bars at their pivotal points upon the starting of said longitudinal shifting.

FRANK L. MANN. 60
